(57) **CLAIM**

The ornamental design for an automobile tire, as shown and
described.

DESCRIPTION

FIG. 1 is a perspective view of an automobile tire showing our
new design;

FIG. 2 is a front view, the top view and the bottom view being
identical thereto;

FIG. 3 is a rear view thereof;

FIG. 4 is a left side view thereof;

FIG. 5 is a right side view thereof;

FIG. 6 is a partially enlarged view taken along lines **6-6** of
FIG. 2; and,

FIG. 7 is a sectional view taken along lines **7-7** of FIG. 6.
The portions of the automobile tire shown in broken lines are
for illustrative purposes only and form no part of the claimed
design.
